US00D837564S

(12) United States Design Patent (10) Patent No.: US D837,564 S
(45) Date of Patent: * Jan. 8, 2019

(54) MAT

(71) Applicant: Mikhail Sheydin, Brooklyn, NY (US)

(72) Inventor: Mikhail Sheydin, Brooklyn, NY (US)

() Term: 15 Years

(21) Appl. No.: 29/624,532

(22) Filed: Nov. 1, 2017

Related U.S. Application Data

(63) Continuation-in-part of application No. 15/474,015, filed on Mar. 30, 2017, and a continuation-in-part of application No. 29/581,733, filed on Oct. 21, 2016, now abandoned, and a continuation-in-part of application No. 29/581,786, filed on Oct. 21, 2016, now abandoned, and a continuation-in-part of application No. 29/581,727, filed on Oct. 21, 2016, now abandoned.
